LUMBER TALLYING DEVICES

Nelson C. Moore, Quesnel, British Columbia, Canada

Application July 11, 1955, Serial No. 521,152

4 Claims. (Cl. 33—169)

My invention relates to improvements in lumber tallying devices.

The objects of the invention are to provide a device capable of keeping a reasonably accurate tally of the output of a planer or other machine which processes lumber of a constant width but of varying standard length; to provide means for measuring the length of each piece of lumber as it is discharged from the planer without impeding its movement and reducing the machine output, and to provide means whereby the device may be quickly adjusted to accommodate a run of lumber which varies in width from the preceding run processed by the machine.

Referring to the accompanying drawings:

Figure 1 is a plan view of the invention.

Figure 2 is an enlarged fragmentary view showing the means for adjusting the angularity of the extension.

Figure 3 is an enlarged detail view of the recording meter plunger.

In the drawings like characters of reference indicate corresponding parts in each figure.

The numeral 1 indicates an elongated table along which pieces of lumber 2 are adapted to be moved endwise. The table is here shown as forming the delivery table for a planer or similar woodworking machine, a portion of which is shown at 4. Machines of this nature are normally provided with discharge rollers, not shown, which would serve to move the lumber along the table in end to end relation substantially as shown in Figure 1. A fence 6 is provided along one side of the table and the opposite side is provided with a fence 7 which terminates intermediate the length of said table. At the outer end of the fence 7 an extension 9 is mounted for swinging movement in the plane of the table and is provided at its inner end with a vertical hinge pin 10 and at its outer end with an adjusting screw 12. The screw engages a nut 14 which is pivotally mounted upon the edge of the table and said screw is secured to the extension as at 15 and is fitted at its free end with a lock nut 16 and a hand wheel 17. The screw 12 serves to swing the extension across the table so that it is disposed at some predetermined angle to the fence 7 and for this purpose the extension is fitted with a pointer 19 which is adapted to read upon a suitably graduated scale 20 mounted upon the table.

The angle I find most suitable for the average length of lumber being processed by planer machines is substantially 175 degrees and in Figure 1 this angle is shown as being bisected by a chain dotted line 22. Disposed upon the line 22 is the plunger 24 of a suitable recording meter 25 which would preferably be one capable of recording the number of each length of lumber, say from 6 to 24 feet in length and in increments of two feet. The oper-

2

ating mechanism of the meter 25 is actuated by movement of the plunger 24, but since the meter does not form part of this invention no further description is considered necessary. A platform 27 is provided below the plane 5 of the table 1 to support the recording meter and the plunger 24 is provided with a stem 28 fitted with a vertical member 29, which member projects upwardly through a slot 30 formed in said table. The vertical member supports at its upper end a slipper 32 which has sliding 10 movement across the table and is adapted to be engaged by the side edge of the lumber being moved lengthwise of the table. The stem 28 of the plunger is mounted in a sleeve 34 which is fitted with a grub screw 35, so that said stem may be adjusted longitudinally of the sleeve to dispose the slipper in the required position determined by the width of the lumber being run through the device. A spring 36 is fitted to the plunger to urge it outwardly of the recording meter. The lengths of lumber are discharged from the planer in alignment with the fence 7 and are urged in the direction of the fence 7 by means of a bell crank 37 which is pivotally mounted as at 38. The bell crank is outwardly curved to form an arm 39 and has an arm 40 which is connected to the table by a spring 41.

25 Before a run of lumber is put through the planer, the tallying device is prepared for use by first adjusting the extension 9, so that it is disposed at an appropriate angle to the fence 7. As previously stated this angle is determined by the length of the lumber being run and also the amount of movement the plunger is required to make to operate the tallying mechanism of the recording meter. The stem 28 of the plunger is adjusted within the sleeve 34 to position the slipper from the outer end of the fence a distance substantially equal to the width 30 of the lumber being run. With the planer in operation the lumber is discharged onto the table with the pieces moving therealong in end to end relation and being held in contact with the fence 7 by the bell crank 37. As the leading end of each length passes from the outer end of 40 the fence onto the extension the slipper 32, which is now bearing upon the adjacent edge of the lumber, commences to move towards the meter by virtue of the fact that said end is now riding up the inclined extension. When the leading and trailing ends of the length are equidistantly spaced from the centre of the plunger or the line 22, said plunger will have been moved inwardly its maximum distance. The lumber length then forms the base of a triangle with the adjacent portions of the fence and the extension forming the other two sides of the 45 triangle. The height of the triangle from the centre of its base to its apex is equal to the movement of the plunger, which in turn is representative of the length of the piece of lumber forming the base of the triangle. Thus the meter is caused to record one piece of lumber 50 of that particular length and each succeeding piece is similarly recorded, so that an accurate tally is kept of the output of the planer, in other words the several lengths of lumber delivered along the discharge table, are registered, together with the length of each.

55 60 65 60 What I claim as my invention is:

1. A lumber tallying device comprising a table along which lengths of lumber adapted to be moved longitudinally, a fence extending along part of one side of said table, an extension extending along said table adjacent the fence and forming an obtuse angle to said fence, a slipper mounted for transverse movement upon the table substantially along a line bisecting the obtuse angle, said slipper being adapted to bear upon the adjacent edge of

a lumber length being moved past the obtuse angle, said length when its ends are equidistantly spaced from the obtuse angle forming the base of a triangle with the adjoining parts of the fence and the extension forming the other two sides of the triangle, said slipper being adapted to be moved transversely by the length of lumber a distance equal to the height of the triangle and proportionate to the longitudinal dimension of the lumber length.

2. A lumber tallying device as claimed in claim 1 wherein the extension is mounted for swinging movement in the plane of the table, and means are provided for selectively varying the angle between the extension and the fence.

10

3. A lumber tallying device as claimed in claim 1, wherein means are provided for varying the normal starting point of the transversely movable slipper from the fence, whereby lengths of lumber of different widths may be tallied.

4. A lumber tallying device as claimed in claim 1, wherein means are provided for urging the lumber lengths into sliding engagement with the fence as it approaches the extension.
